UNITED STATES PATENT OFFICE.

JAMES W. FULLER, OF CATASSAUQUA, PENNSYLVANIA.

DESIGN FOR A BICYCLE AMMONIA-GUN HOLDER.

SPECIFICATION forming part of Design No. 27,766, dated October 19, 1897.

Application filed September 2, 1897. Serial No. 650,403. Term of patent 14 years.

To all whom it may concern:

Be it known that I, JAMES W. FULLER, a citizen of the United States, residing at Cata-
sauqua, in the county of Lehigh and State of
Pennsylvania, have invented and produced
a new and original Design for a Bicycle Am-
monia-Gun Holder, of which the following is
a specification, reference being had to the ac-
companying drawings, forming part hereof,
in which—

Figure 1 is a perspective view of the bi-
cycle ammonia-gun holder of my design, and
Fig. 2 is a vertical central sectional view of
the same.

15 The two views are deemed essential or nec-
essary in order to disclose the leading features
of design of my said invention, which con-
sists of the particular shape or configuration
of the ammonia-gun holder for application to
20 a bicycle or similar appliance.

Referring to the drawings, *a* represents the
rear concaved attaching member of the holder
having substantially flat perforated seats *b*
and *b'*, and formed integral with the same is
25 a ring *e*, which merges in a forward direction
into two parallel rectangular arms *d* and *d'*,

arranged close together, so as to hold or sup-
port between them a soft-nozzle ammonia-
gun, and each of the said arms flaring out-
ward and curved to form together a small 30
ring-clasp *e* for the reception of a hard-nozzle
ammonia-gun and flaring outward in front
from the points *f* and *f'* to form a throat and
terminating in a mouth *F*, the ends of which
ring clasp or holder are bent over, forming 35
the ends *f²* and *f³*. The flaring end of the
throat and mouth *F* permits of a gun in either
of the forms mentioned being inserted and
supported between the parallel arms *d* and *d'*,
or in the ring clasp or holder *e* of the device. 40

Having thus described my invention, what
I claim as new, and desire to secure by Let-
ters Patent, is—

The design for a bicycle ammonia-gun
holder, substantially as shown and described. 45

In testimony whereof I have hereunto set
my signature in the presence of two subscrib-
ing witnesses.

JAMES W. FULLER.
